STORAGE CABINET FOR MAGNETIC TAPES OR OTHER SIMILAR ARTICLES

John Bower, Shelby, N.C., assignor to
American Greetings Corporation

Filed May 1, 1974, Ser. No. 465,872

Term of patent 14 years

Int. Cl. D6—04

U.S. Cl. D6—149

FIG.1

FIG.2

FIG.3

FIG.4

FIG.5

FIG.6

FIG.7

FIG.8

FIG.9

FIG.10

FIG.11

FIG.12

FIG.13

FIG.14

FIG.15

FIG. 1 is a top plan view of a storage cabinet for magnetic tapes or other similar articles embodying this new design;

FIG. 2 is a bottom plan view thereof;

FIG. 3 is an elevational view taken generally along the plane of line 3-3 of FIG. 1, looking in the direction of the arrows;

FIG. 4 is an elevational view taken generally along the plane of line 4-4 of FIG. 1, looking in the direction of the arrows;

FIG. 5 is an elevational view taken generally along the plane of line 5-5 of FIG. 1, looking in the direction of the arrows;

FIG. 6 is a horizontal sectional view taken generally along the plane of line 6-6 of FIG. 3, looking in the direction of the arrows;

FIG. 7 is a perspective view with one of the three access doors of the cabinet in an opened position;

FIG. 8 is a top plan view of a modified cabinet embodying the invention;

FIG. 9 is a bottom plan view thereof;

FIG. 10 is a horizontal sectional view taken generally along the plane of line 10-10 of FIG. 11, looking in the direction of the arrows;

FIG. 11 is an elevational view taken generally along the plane of line 11-11 of FIG. 8, looking in the direction of the arrows;

FIG. 12 is an elevational view taken generally along the plane of line 12-12 of FIG. 8, looking in the direction of the arrows;

FIG. 13 is an elevational view taken generally along the plane of line 13-13 of FIG. 8, looking in the direction of the arrows;

FIG. 14 is an elevational view taken generally along the plane of line 14-14 of FIG. 8, looking in the direction of the arrows; and

FIG. 15 is a perspective view with one of the three access doors of the cabinet of FIGS. 8-14 in an opened position.

I claim:

The ornamental design for a storage cabinet for magnetic tapes or other similar articles, substantially as shown and described.
